UNITED STATES PATENT OFFICE

CLEMENT L. STEPHENSON, OF ROCHESTER, NEW YORK, ASSIGNOR OF ONE-HALF TO
WEGMAN-WALSH PRESS, INC., OF ROCHESTER, NEW YORK, A CORPORATION OF
NEW YORK

DESIGN FOR A TOY BUILDING

Application filed May 23, 1932. Serial No. 43,881. Term of patent 3½ years.

To all whom it may concern:

Be it known that I, CLEMENT L. STEPHENSON, a citizen of the United States, residing at Rochester, in the county of Monroe and State of New York, have invented a new, original, and ornamental Design for a Toy Building, of which the following is a specification, reference being had to the accompanying drawing forming part thereof.

In the drawing:

Fig. 1 is a side elevation of a toy building, showing my new design;

Fig. 2 is a front view thereof, and

Fig. 3 is a perspective view.

I claim:

The ornamental design for a toy building substantially as shown.

CLEMENT L. STEPHENSON.
